United States Patent Office

Des. 191,684
Patented Oct. 31, 1961

191,684

BOTTLE

Clarence A. Price, Ann Arbor, and Donald P. Denhoff,
Saline, Mich., assignors to Plas-Tainer Inc., Saline,
Mich., a corporation of Michigan

Filed Nov. 25, 1960, Ser. No. 62,982

Term of patent 14 years

(Cl. D58—8)

FIGURES 1, 2 and 4 are front and side elevational views and a top plan view, respectively, of a bottle, showing our design; and,

The dominant features of our design reside in the portions shown in full lines.

We claim:

The ornamental design for a bottle, substantially as shown and described.
